UNITED STATES PATENT OFFICE.

LEWIS WILLIAMS, OF JOHNSTOWN, PENNSYLVANIA.

ATTACHMENT FOR METAL-PUNCHING MACHINES.

SPECIFICATION forming part of Letters Patent No. 627,033, dated June 13, 1899.

Application filed March 17, 1899. Serial No. 709,486. (No model.)

To all whom it may concern:

Be it known that I, LEWIS WILLIAMS, a citizen of the United States, residing at Johnstown, in the county of Cambria and State 5 of Pennsylvania, have invented certain new and useful Improvements in Attachments for Metal-Punching Machines, of which the following is a specification, reference being had therein to the accompanying drawings.

10 This invention relates to machines for punching metals.

The object of the invention is to produce an attachment for connection to a punching-machine, punching-press, or like machine, 15 which attachment supports the punching-tool and permits the movement of such tool to different positions under the press or plunger, whereby a plate or other object to be punched may have a number of holes punched there- 20 in, if desirable, without necessity for the movement of the plate itself—that is, the tool is moved to the work instead of the work moving to the tool, as is the usual practice.

Figure 1 is a plan or diagram indicating a 25 punching press or machine of any usual construction and indicating in full lines and dotted lines the positions which may be reached by the punch under the plunger. Fig. 2 is a partial side elevation and partial section of 30 the attachment, parts of the punching-machine being indicated in dotted lines. Fig. 3 is a sectional detail of a modified punch and feeler, the punch being in two parts M' M'', connected by a screw-threaded joint.

35 A indicates a punching machine or press of any usual construction and provided with a vertically-reciprocating plunger B, which is under control of the operator and is caused to move by a lever or treadle operating a suitable motive power. The plunger B has a 40 plane lower face and does not directly carry the punching-tool.

C denotes the machine bed or anvil, having a plane face, as usual, and being parallel with the plane face of plunger B.

45 Connected to some part of the frame of the machine A there is a bracket 1. A yoke D' is pivoted to the bracket 1 by a pintle 2 or otherwise. This yoke, as shown, has integral 50 top and bottom bars and connecting-standards, such being a convenient, but not an es-

ential, construction. The joint between the yoke and bracket may have antifriction-balls 3 to insure an easy movement about the pivot 2.

To the outer or swinging end of yoke D' a second yoke D is pivoted by a pintle 5 or other suitable connection. This yoke D, as shown, has top and bottom bars or arms connected by an integral vertical standard, and the joint 60 between the two yokes may be a ball-joint 6. When thus constructed and connected, the yoke D' may swing in a plane about pintle 2 and the yoke D may swing in the same plane about pintle 6 while partaking of the movement of the first yoke. The outer end of yoke D therefore has a wide range of movement in a plane parallel with the face of the plunger B and the anvil C and may be moved to any position between the plunger and the anvil. The 65 upper and lower arms of yoke D are preferably in line at their outer ends, so that the punch and die will be in alinement with each other.

The lower arm or bar of yoke D carries a 75 seat 8, having a passage 7 therein and a recess for the reception of the die F, corresponding to the punch to be used. The die F is held in its seat by set-screw 9 or by other suitable means and can be changed on occasion. The 80 disks cut from the work by the punch escape through passage 7.

The upper arm of yoke D has a vertical recess to receive the punch-holder L, to which holder the punch E is connected by a screw- 85 collar J or in other suitable manner.

The holder L has a shoulder 10 near its upper end. A strong spiral spring K surrounds the holder in recess in the yoke D and tends to lift the holder and punch. The collar J limits 90 this movement by its engagement with the arm of the yoke.

The punch E has a transverse slot and a vertical perforation and may be in one or more parts. (See Fig. 3.) A sleeve P surrounds the body of the punch, being held thereto by a pin 11 passing through the slot. This sleeve is a hand-grasp for the operator, and by taking hold of this sleeve the punch may be swung anywhere within its limit of 95 movement, and as the die F on the lower arm of the yoke partakes of the movement the punch 100

and die are necessarily in alinement and the punch is in position to be driven down by the plunger.

The vertical recess in the punch contains the centering prick or feeler I, which feeler has a head within the punch, and a sharpened or rounded point may project below the punch. A spring M surrounds the feeler and pushes its head up against the pin 11, thus lifting the sleeve or handle P.

A stripper or presser foot H is connected to the outer end of the yoke D by bolts or otherwise.

The plate G or other article to be punched is supported on rolls 12 or other convenient supports, so that the body of the plate extends between the bed or anvil C and the follower B. Preferably the rolls or supports 12 will hold the plate so far above bed C that the die F may be easily swung between the bed and plate, and the punch will then swing above the plate. The punch and die will preferably be relatively so adjusted that there is not much more than room for the work between the punch and die.

The plate G will be marked, preferably, by a prick-punch in the various places which are to be punched by the machine, and when placed on supports 12 the punch is swung under follower B. The operator, pressing down on sleeve P, projects the feeler I until it enters one of the pricks in the plate. Then by his foot or other hand he throws plunger B into operation. This plunger falls on holder L and drives down the punch through the plate, the disk or fillet dropping through the hole or opening 7. As soon as the downward pressure of the hand on sleeve P is released the feeler rises under the impulse of spring M. As soon as plunger B rises the spring K lifts the punch and its holder, the stripper H holding down the work.

Much of the work for which this machine is specially useful is in punching holes in boiler or similar plates. These plates may be supported a little above the die and will yield by their own elasticity when the punch falls, so as to be seated firmly on the die; but rolls or supports 12 might be elastically supported, if desirable.

Yoke D might be slightly elastic, so as to support the die-seat far enough above the bed C to permit easy movement. The action of the plunger B will seat all the parts firmly when the plunger falls. As a punch supported in this manner can be very quickly shifted from point to point between plunger B and bed C, there is considerable advantage in economy and accuracy of work over the usual method of shifting the plate to the punch, which reciprocates always in the same line.

Modifications within the scope of my claims are contemplated.

What I claim is—

1. An attachment for a punching-machine provided with flat anvil and reciprocating flat-faced plunger, said attachment consisting of a yoke pivoted to swing in the plane of the anvil and plunger and having parallel arms, a recessed die carried by one arm of the yoke and a punch carried by the other arm of the yoke, and a handle by which the yoke may be swung so as to carry the punch and die to the work between the plunger and anvil, substantially as described. 65

2. In an attachment for punching-machines, a swinging yoke pivoted to the frame of the machine, a second two-armed yoke pivoted to the outer end of the first and swinging in the plane of the machine plunger and bed, a die carried by one arm of the second yoke, and a punch and lifting-spring carried by the other arm in line with the die, all combined substantially as described. 70

3. In an attachment for punching-machines, a swinging two-armed yoke, a die carried by one arm of the yoke, and a punch carried by the other arm and having means for lifting the punch, and a hand-grasp consisting of a sleeve surrounding the punch-body, all combined substantially as described. 85

4. In an attachment for punching-machines, a swinging yoke carrying a punch, the body of the punch slotted transversely and perforated longitudinally, a pointer-feeler in the perforation of the punch, and a sleeve surrounding the punch and operating on the feeler by a connection through the slot in the punch-body, substantially as described. 95

5. In an attachment for punching-machines, the punch having a central passage with a spring-lifted feeler therein, and a handle surrounding the punch and connected to the feeler so that the same may be depressed by the action of the handle, substantially as described. 105

6. In a punching-machine, the combination of supports for the work outside the bed of the machine proper, a two-armed yoke carrying on one arm the die which may be swung under the work and above the bed of the machine, and on the other arm a punch which maintains its alinement with the die but swings above the work under the machine-plunger, and a handle by which the yoke may be swung, all substantially as described. 110

In testimony whereof I affix my signature in presence of two witnesses.

LEWIS WILLIAMS.
